Des. 202,545
Patented Oct. 19, 1965

202,545

FLOOR, WALL, AND SERVICE UNIT FOR A STORE INTERIOR

Jerome Gould, Los Angeles, Calif., assignor to A & W
Root Beer Co., Santa Monica, Calif., a corporation of
California

Filed July 13, 1964, Ser. No. 80,821

Term of patent 14 years

(Cl. D13—1)

Fig. 4

Fig. 5

Fig. 6

FIGURE 1 is a front perspective view of a floor, wall, and service unit for a store interior showing my new design;

FIGURE 2 is a top plan view;

FIGURE 3 is an elevational view of a decorative transverse beam member forming a part of said store interior;

FIGURE 4 is a left-hand side elevational view;

FIGURE 5 is a right-hand side elevational view; and

FIGURE 6 is a decorative rear panel forming a part of said store interior.

The exterior walls of the floor, wall, and service unit of the store interior are plain and unornamented.

I claim:

The ornamental design for a floor, wall, and service unit for a store interior, substantially as shown and described.
